UNITED STATES PATENT OFFICE.

GEORGE A. LUTZ, OF PLAINFIELD, NEW JERSEY, ASSIGNOR TO AMERICAN CIRCULAR LOOM COMPANY, OF PORTLAND, MAINE, A CORPORATION OF MAINE.

ELECTROPLATING APPARATUS.

1,022,561.

Specification of Letters Patent.

Patented Apr. 9, 1912.

Application filed January 7, 1911. Serial No. 601,345.

To all whom it may concern:

Be it known that I, GEORGE A. LUTZ, a citizen of the United States, and resident of Plainfield, in the county of Union and State 5 of New Jersey, have invented certain new and useful Improvements in Electroplating Apparatus, of which the following is a specification.

My invention relates to improvements in 10 electroplating and has for its object to provide a comprehensive system adapted to the plating of relatively long articles, such as pipes and conduits, whereby a quantity of articles may be simultaneously plated with 15 expedition and efficiency.

The nature of my invention and the manner of carrying the same into effect will be more fully hereinafter set forth and then pointed out in the claims.

Reference is to be had to the accompanying drawings forming part hereof, wherein,

Figure 1 is a diagrammatic plan view illustrating various tanks and devices utilized in the plating; Fig. 2 is a similar view, 25 enlarged, of tanks shown in Fig. 1, in connection with which the electric current is used; Fig. 3 is a sectional view through several of the tanks; Fig. 4 is a sectional view through one of the plating tanks; Fig. 30 5 is an enlarged sectional view, part being broken away, through one of the plating tanks; Fig. 6 is an enlarged plan view of plating tank D; Fig. 7 is an enlarged detail view illustrating the supports and electrical connections for the cathode frame or 35 spider; Fig. 8 is a plan view of the cathode frame or spider; Fig. 9 is a section on the line 9, 9, in Fig. 8; Fig. 10 is a detail section of part of the cathode spider; Fig. 11 40 is a plan view of the plating tank showing the cathode spider in position; Fig. 12 is a detail section, enlarged, on the line 12, 12, in Fig. 11.

Similar numerals of reference indicate 45 corresponding parts in the several views.

In the arrangement shown in Fig. 1 I provide a tank A to contain metal cleaning material, such as alkali, and I provide means for passing the electric current through the 50 solution in said tank while the alkali is cleaning the articles to be plated; adjacent tank A is a tank B containing hot water, and at C is a tank containing pickling acid; at D is a tank in which a preliminary or 55 light metal coating, say of copper, may be

deposited upon articles to be plated, suitable means being provided for passing electric current through the electrolyte in tank D as hereinafter described; at E is a tank to contain water for cleaning the articles 60 removed from tank D; at F is a tank arranged substantially similar to tank D in which the final electro-deposit upon the articles may be made, and at G is a tank to contain hot water, into which the plated articles are dipped when removed from tank F. By the arrangement of parts so far set forth, the articles to be plated may first be dipped 65 in the alkali solution in tank A for a suitable period, during which time electric current flows through the solution to aid in dislodging grease and other matter upon the pipes or articles to be plated; the articles are then immersed in the hot water in tank B, and then allowed to rest in the pickling 70 solution in tank C for a suitable period, and said articles may be again dipped in the water in tank B whereupon they are placed in the electrolyte in tank D, to receive a preliminary electro-deposit, as of copper or 75 other suitable metal; the articles are then removed from tank D and immersed in the water in tank E to remove electrolyte and other matter adhering to the articles from the solution in tank D and then said articles are placed in the electrolyte in tank F to receive a desired or final coating of 80 zinc or other metal, and when the articles are removed from the tank F they are immersed 85 in hot water in tank G for final cleaning.

With the arrangement shown the tank A is made of metal and is shown provided with an inner hollow or tubular wall A² (Figs. 1 and 2) serving in the nature of an anode or conductor, the tank A and its inner chamber within wall A² containing an alkali solution, such as a solution of potash. The wall of tank A is connected with one side of an electric circuit, as the positive conductor 1 thereof, the walls of the tank thus serving in the nature of an anode; the opposite or negative conductor 2 connects with one or more metallic supports 3 extending above and shown projecting partly over the tank, which supports are adapted to receive a cathode spider or frame 4, (Fig. 8) from which articles to be plated are hung. The supports 3 are shown arranged 100 in connection with all of the tanks, and the 105 110

- description thereof to be made in connection with tank D will give an understanding of the general arrangement of such supports in connection with the various tanks.
- 5 At 5 is piping or a coil arranged in any suitable manner in tank A for the purpose of heating the solution therein, and such piping may have a branch 6 controlled by a suitable valve for admitting live steam into
- 10 such solution when required (Figs. 1 and 2). The arrangement is such that when spider 4 is mounted upon supports 3 current will flow from conductor 1 and the walls of the tank through the solution to the articles hanging from spider or frame 4, and thence from the spider through conductor supports 3 to conductor 2, whereby a high efficiency for cleaning metal articles with an alkali solution is effected. Tank B (Fig. 1) is provided with a steam pipe or coil 7 for heating the water therein, and tank C is also provided with a steam coil 7. A water pipe 8 (Fig. 3) is shown provided with a branch 9 leading to tank C and having a branch 10 leading to tank D. Tank D is also shown provided with a suitable steam coil or piping 11 for heating the electrolyte therein, (Figs. 1 and 2). At 12 is a water pipe leading to tank E (see Figs. 1 and 3). Tank F is shown provided with a suitable steam pipe or coil 13 for heating the electrolyte therein, and at 14 is a water pipe leading to tank F, (see Figs. 1 and 2). At 15 is a steam pipe leading to tank G for heating the water therein. The steam or water pipes may be arranged in any other suitable manner and provided with cocks to control the flow. By this means the temperature and strength of the solutions and water used in the operation may be controlled as required.
- 15 The tanks D and F are arranged to contain any desired number of suspended anodes, and as both of said tanks may be similarly arranged, a description of parts respecting tank D will suffice for both tanks.
- 20 At 16 (Figs. 3, 4, 5, 6 and 7) is a conductor suspended from tank D, as by brackets 17 secured to the tank, to one or more of which brackets the conductor 1 is connected. From conductor 16 suitable anodes 18 are suspended, as by hooks 19 connected with the anodes, whereby said anodes may be readily removed as required. In order to hang a relatively large number of anodes within the tank I provide several conductors 16, 16^a, 16^b, shown concentrically arranged and electrically connected together, as by one or more conductors 20 (see Fig. 6), connecting with the conductors 16, 16^a, 16^b. The conductor 16^a is shown supported upon posts 21 (Fig. 5) extending upwardly from the bottom of the tank, the clips 16^c which connect conductor 16^a with conductor 20 resting upon said posts. A centrally disposed post
- 22 (Figs. 3, 4 and 5) in the tank is shown provided with a head or cross bar 22^a upon which the conductor 16^b rests, clips 16^d holding said conductor 16^b to conductor 20. Near the lower part of the tank is a bar 24 (Figs. 3, 4 and 5) supported by posts 21, and shown provided with a groove 24^a in its upper face into which the lower ends of anodes 18 project, whereby said anodes are retained in place.
- 25 A bar or plate 25 (Figs. 4 and 5) is supported on post 22 and provided with a groove 25^a to receive the lower ends of the corresponding anodes. The arrangement is such that the anodes may be applied and removed as required and spaces are provided between the several series of anodes into which spaces the articles or pipes to be plated may be passed.
- 30 The cathode spider or frame 4 (Figs. 8 to 12) is shown provided with a central metallic plate or head 4^a from which conductor rods or arms 4^b project outwardly or radially and to which said rods are suitably secured.
- 35 At 4^c, 4^d are conductors secured to conductor rods or arms 4^b, as by clips 4^e, the conductors 4^c being shown annular and of such dimensions as to lie respectively between the conductors 16, 16^a and 16^a, 16^b, when the spider or frame 4 is placed over the tank with the ends of its conductor arms 4^b resting in the supports 3 (see Fig. 11).
- 40 Head or plate 4^a is provided with a rod or hook 4^f for connection with any suitable tackle from an overhead crane or other device for raising and lowering and moving the spider about with its attached articles to be plated. The conductors 4^c, 4^d of the cathode spider or frame 4 are shown provided with suspension devices 4^f (Figs. 9, 10 and 12), shown in the form of hooks to which conduits, pipes or other articles *x* to be plated are suitably attached.
- 45 The cathode spider or frame 4 is to be attached to supports 3 so as to make electrical contact therewith, the arrangement for which purpose I have shown being as follows: At 26 is a post for each support 3 (Figs. 3, 4, 7 and 12) shown located adjacent the corresponding tank and resting upon floor 27, and upon each post is a head 28, shown provided with jaws 28^a between which is pivotally attached the support 3 adapted to support arms 4^b, (see Figs. 6, 7 and 11). Supports 3 are shown provided with recesses or sockets 3^a in their upper surfaces (Fig. 12) in which arms 4^b rest to retain said arms in proper position. Clamping devices are provided for firmly connecting arms 4^b to supports 3 to provide good electrical contact. The clamping devices I have shown comprise bails or arms 29 having cross pins 30 carried in slotted keepers 31 on the under sides of supports 3, (Figs. 7 and 130

12,) said bails having heads 3^b provided with slots 3^c receiving pins 3^d carried by bails or arms 29, and at 32 are levers hung upon pins 3^d and having suitable cam like faces 5 at their lower ends to engage the heads 3^d (Fig. 12.) The arrangement is such that the clamping devices may be moved to one side, as in Fig. 12, free from the arms 4^b, to permit the setting of the same upon supports 3 10 or the removal of the arms therefrom, and the clamping devices may be moved along supports 3 to engage arms 4^b upon said supports by swinging lever 32 as required, as indicated in dotted lines in Fig. 12, and in 15 full lines in Figs. 6 and 11. The conductor 2 is connected with one or more supports 3, for which purpose I have shown a block 2^a (Figs. 7 and 12) at the end of the conductor adapted to be secured to a contact 3^e on support 3, as by a screw *a*, whereby conductors 2 may readily be detached from supports 3 when desired. The arms 4^b may have copper plates 4^g (Fig. 12) secured on their under surface to make good electrical connection with the conductors 4^c, 4^d, by means 20 of the clamps 4^e, and the supports 3 may have copper contact plates 3^h secured thereto, while the other parts of the supports may be of steel or iron, whereby strength is provided with good conducting surface.

When plating of a large number of articles simultaneously is to be done, such as pipes, conduits and the like, the anodes are placed in position within the tanks, articles are 35 hung from the cathodes spider or frame, the tanks being supplied with the various solutions or electrolytes, and then the spider is lowered over tank A and rests upon the supports 3, so that the articles will be immersed 40 in the alkali solution, the current flowing through such solution, the articles and the spider. When the articles have remained in the solution a sufficient length of time, the cathode spider is raised and the articles 45 are then lowered into the hot water in tank B, and then the articles are placed in the pickling acid in tank C and they are again immersed in the hot water in tank B. From there the spider is removed and the 50 articles are inserted in the electrolyte in tank D, the arms of the cathode spider being placed upon adjacent supports 3 and secured in position by the clamping devices, the articles to be plated then being located 55 between the corresponding series of anodes. After sufficient plating, as a light coating of copper upon the articles, the spider is released and raised from tank D, the articles 60 are immersed in the water in tank E, and then the spider with the articles is lowered over tank F, the arms of the spider being secured to the supports 3 in manner before described, and the current allowed to flow until the zinc or other metal is suitably 65 deposited upon the articles, whereupon the

spider is released and removed and the articles immersed in the hot water in tank G for final cleaning. It will thus be seen that a large number of articles may be put through the several steps required in succession while remaining attached to the cathode spider, merely requiring the raising and lowering of the spider and the transfer of the same from tank to tank.

It will be seen that the circuits 1, 2 of the 75 tanks A, D and F (Figs. 1 and 2) are arranged in multiple and by means of suitable switches several of the tanks may be supplied with current simultaneously, so that the plating steps may take place 80 simultaneously in different tanks with different sets of articles carried by several cathode spiders or frames, whereby the operation may be carried on expeditiously. While I have described various steps of 85 immersing the articles to be plated in solutions, electrolyte, etc., it will be understood that such steps may be varied as required, also that changes may be made in the arrangements set forth without departing 90 from the spirit of my invention.

Having now described my invention what I claim is:

1. An electroplating apparatus comprising a tank, a plurality of conductors spaced apart adjacent the tank, means to suspend anodes from said conductors, a cathode provided with means to suspend articles to be plated between such anodes, and supports for the cathode adjacent to the wall of the 95 tank and insulated from said conductors.

2. An electroplating apparatus comprising a tank, a plurality of conductors spaced apart adjacent the tank, means to suspend anodes from said conductors, a cathode provided with means to suspend articles to be plated between such anodes, supports for the cathode adjacent to the wall of the tank 105 and insulated from said conductors, and posts supported adjacent the tank and carrying said supports.

3. An electroplating apparatus comprising a tank, a plurality of conductors spaced apart adjacent the tank and located in the same circuit, means to suspend anodes from said conductors, a cathode provided with means to suspend articles to be plated between such anodes, supports for the cathode adjacent to the wall of the tank and insulated from said conductors, and means for 115 removably securing the cathode to said supports.

4. An electroplating apparatus comprising a tank, a conductor adjacent the tank, means to suspend anodes from said conductor, a cathode provided with means to suspend articles to be plated between such anodes, supports for the cathode adjacent to the wall of the tank and insulated from 125 said conductor, said supports having bails 130

and levers connected with said bails for securing the cathode upon the supports.

5. An electroplating apparatus comprising a tank, a conductor adjacent the tank, means to suspend anodes from said conductor, a cathode provided with means to suspend articles to be plated between such anodes, supports for the cathode adjacent to the wall of the tank and insulated from said conductor, said supports having bails and levers connected with said bails for securing the cathode upon the supports.

6. An electroplating apparatus comprising a tank, a conductor adjacent the tank, means to suspend anodes from said conductor, a cathode provided with means to suspend articles to be plated between such anodes, supports for the cathode adjacent to the wall of the tank and insulated from said conductor, said supports having bails, heads movably connected with said bails and levers for clamping said heads upon the cathode.

7. An electroplating apparatus comprising a tank, a plurality of conductors spaced apart adjacent the tank, means to suspend anodes from said conductors, a cathode provided with means to suspend articles to be plated between such anodes, supports for the cathode adjacent to the wall of the tank and insulated from said conductors, bails adjustably connected with said supports, and levers connected with said bails for securing the cathode to the supports.

35 8. An electroplating apparatus comprising a tank, a conductor adjacent the tank, means to suspend anodes from said conductor, a cathode provided with means to suspend articles to be plated between such anodes, supports for the cathode adjacent to the wall of the tank and insulated from said conductor, said supports having keepers, bails slidably connected with said keepers and levers connected with the bails for securing the cathode to the supports.

9. An electroplating apparatus comprising a tank, annular conductors spaced apart, one of said conductors being supported by the tank, a base supporting the inner conductor, means for supporting an intermediate conductor whereby spaces are formed between said conductors, means to support anodes upon said conductors, a cathode having means to support articles to be plated in the spaces between said anodes, and means for supporting said cathode separate from said conductors.

10. An electroplating apparatus comprising a tank, annular conductors spaced apart, one of said conductors being supported by the tank, a base supporting the inner conductor, a plurality of posts supporting an intermediate conductor whereby spaces are formed between said conductors, means to support anodes upon said conductors, a

cathode having means to support articles to be plated in the spaces between said anodes, and means for supporting said cathode separate from said conductors.

11. An electroplating apparatus comprising a tank, annular conductors spaced apart, one of said conductors being supported by the tank, a base supporting the inner conductor, a plurality of posts supporting an intermediate conductor whereby spaces are formed between said conductors, means to support anodes upon said conductors, a cathode having means to support articles to be plated in the spaces between said anodes, means for supporting said cathode separate from said conductors, a conductor rod secured to said first named conductors, said rod being secured to said posts, a cathode having means to support articles to be plated within said spaces and means to support said cathode independent of said conductors.

12. An electroplating apparatus comprising a tank, a plurality of spaced concentrically disposed conductors located over the tank and electrically connected, means to suspend anodes from said conductors, and a cathode having concentrically disposed supports spaced between said conductors for supporting articles between said anodes.

13. An electroplating apparatus comprising a tank, means for supporting anodes therein, a member in the lower part of the tank having a recess receiving the anodes, a cathode provided with means to support articles to be plated, and means to support the cathode independent of said anodes.

14. An electroplating apparatus comprising a tank, a conductor adapted to support anodes therein, a plurality of posts, a conductor supported by said posts, a grooved member connected with said posts to receive anodes suspended from said conductor, a centrally disposed post having a conductor to support anodes and provided with a grooved member to receive anodes supported by the post, a cathode provided with means to support articles to be plated within the tank, and means to support said cathode independent of said anodes.

15. A cathode for an electroplating apparatus comprising a plurality of outwardly disposed arms and a plurality of annularly disposed conductors connected with said arms, said arms projecting beyond the outer conductor to engage contacts.

16. A cathode for an electroplating apparatus comprising a centrally disposed conductor plate, outwardly disposed conductor arms secured to said plate and annularly disposed conductors connected to said arms, the outer ends of said arms projecting beyond the outer conductor.

17. A cathode for an electroplating apparatus comprising a centrally disposed metal head, radially disposed arms secured to and

- projecting from said head, and concentric circularly disposed conductors spaced apart and secured to said arms.
18. An electroplating apparatus comprising a tank, means for supporting anodes therein, inwardly disposed supports adjacent the top of the tank, a cathode spider having outwardly disposed arms carried by said supports and provided with conductors secured to said arms, and means for supporting articles from said spider.
19. An electroplating apparatus comprising a tank, means to support anodes therein, conductor supports located above the tank and extending inwardly thereof, a cathode provided with arms carried by said supports, and means for suspending articles from said arms.
20. An electroplating apparatus comprising a tank, means to support anodes therein, conductor supports located above the tank and extending inwardly thereof, a cathode provided with outwardly disposed arms carried by said supports, circularly disposed conductors connected with said arms, and means to support articles from said conductors.
21. An electroplating apparatus comprising a tank, means to support anodes therein, posts adjacent said tank, supports carried by said posts and projecting inwardly radially of the tank, a cathode having radially disposed arms carried by said supports, and means to support articles from said cathode.
22. An electroplating apparatus comprising a tank, means to support anodes therein, posts adjacent said tank, supports carried by said posts and projecting inwardly radially of the tank, a cathode having radially disposed arms carried by said supports, said cathode having radially disposed arms carried by said supports, and means to support articles from said cathode.
23. In an electroplating apparatus the combination of a plurality of tanks each tank being provided with a conductor, and means to suspend anodes therefrom, each tank also being provided with a plurality of supports for cathodes adjacent the upper part of the tank, said conductors being connected in multiple with one side of a circuit and said supports being connected in multiple with the opposite side of said circuit.
24. In an electroplating apparatus the combination of a plurality of tanks each tank being provided with a conductor, and means to suspend anodes therefrom, each tank also being provided with a plurality of supports for cathodes adjacent the upper part of the tank, said conductors being connected in multiple with one side of a circuit and said supports being connected in multiple with the opposite side of said circuit, and a cathode provided with arms to be supported by said supports, and means for suspending articles to be plated from said cathode.

Signed at New York city, in the county of New York and State of New York this 31st day of December, A. D. 1910.

GEORGE A. LUTZ.
